UNITED STATES PATENT OFFICE.

JAMES K. LANNING, OF BOSTON, MASSACHUSETTS.

WARP STOP-MOTION FOR LOOMS.

No. 861,217.

Specification of Letters Patent.

Patented July 23, 1907.

Application filed February 12, 1907. Serial No. 357,077.

To all whom it may concern:

Be it known that I, JAMES K. LANNING, a citizen of the United States, residing at Boston, in the county of Suffolk, State of Massachusetts, have invented an 5 Improvement in Warp Stop-Motions for Looms, of which the following description, in connection with the accompanying drawings, is a specification, like letters on the drawings representing like parts.

My invention relates to looms, being more particularly concerned with but not limited to the provision of improvements to be used in connection with electrical warp stop motions.

My invention will be best understood by reference to the following description when taken in connection 15 with the accompanying illustration of one specific embodiment thereof, while its scope will be more particularly pointed out in the appended claims.

In the drawings:—Figure 1 shows in side elevation a loom frame with attachments applied thereto embodying one form of my invention; Fig. 2 shows in plan a lease rod bracket embodying one form of my invention; Fig. 3 is a side elevation of such form of bracket; Fig. 4 is an end elevation thereof; Fig. 5 is a plan of a modified form of bracket embodying my 25 invention; Fig. 6 is a side elevation of such modified form of bracket; Fig. 7 is an end elevation of such modified form of bracket; Fig. 8 is a side elevation of still another form of bracket embodying my invention; Fig. 9 is a view partly in end elevation and 30 partly in vertical section of such modified form of bracket; Fig. 10 is a central sectional view of the portion of the loom supporting the lease rod bracket, and Fig. 11 is a transverse sectional view of the same.

In the drawings, I have shown my invention as 35 applied to a particular construction of loom and a particular type of warp stop motion, but it is to be understood that such is for the purpose of illustration only, and that my invention in its various embodiments may be adapted to looms and stop motions 40 of other and quite different types whether electrical or mechanical.

Referring to the drawings, I have illustrated the side frame member 1 of a loom provided with a well-known construction of belt shifting device, which is 45 thrown into operation through the action of the drop bars of the warp stop motion in a manner well understood to those skilled in the art, it being unnecessary to describe in detail the construction and operation of such belt shifting device. In the present instance, I 50 have shown the loom as provided with circuiting devices for the warp stop motion of the same general construction as is described in Patent, No. 690,636 to Coldwell & Gildard. To the side frame members 1 are adjustably bolted the upright angle brackets 2 55 (Fig. 1) which sustain various contact devices for the

warp stop motion. These comprise primarily the single tubular contact bar 3, supported at its ends by the wooden plugs 4, the latter secured to inwardly projecting lugs upon the angle brackets 2. Connection is had between the tubular contact bar 3 and one side of the circuit, leading to the controlling magnet by means of the spiral coil 5 of conducting wire, which connects with the lead wire 6 passing through the adjacent wooden plug 4 and the insulating tube 7 to the controlling magnet 36. The other side of the 60 circuit, as will be well understood by those well skilled in the art, is connected through the frame of the machine to the pair of overhead circuit and guiding rods 8, which are shown as converging toward their upper edges and secured at their opposite ends to lugs projecting inwardly from the bracket 2.

In the present type of my invention, supported above the contact rods 8 upon the lease rod bracket 9 and engaging at their ends with inturned studs sustained by said brackets are the tubular lease rods 10 and 75 11, which maintain the threads of the warp in a leased condition with successive threads crossed in a fashion well understood to those well skilled in the art.

Upon successive warp threads are suspended the drop bars, the latter arranged in two sets, the drop bar 12 of one set being sustained by one series of threads and having their open depending legs embracing one of the circuit rods, and the drop bar 13 of the other set being sustained by the other series of threads and embracing the other circuit rod. In the illustrated 80 construction as in the aforesaid prior patent, No. 690,936, the drop bars are provided with closed longitudinal slots 14, 15, through which passes a transverse retaining rod, the rod for one set of bars being represented at 16, and the rod for the other set at 17. The 90 ends of the said retaining rods pass through apertures in the bracket 2, which apertures, however, are closed after the rods are placed in position by the overlying walls of the lease rod brackets 9.

The drop bars or detectors are maintained in accurate 95 contact with the contact rods 8 under all conditions of use. A break in one of the warp threads causes the drop bar supported thereby to fall and contact with the contact bar 3, completing the circuit and energizing the electro-magnet controlling the device for the 100 immediate stoppage of the loom.

It is quite desirable that the leasing members 10 and 11 however mounted with relation to each other, should so control the position of the threads that the desirable relation between the drop bars and the co-operating contact device should be maintained without displacement, otherwise vibratory movement of the lay may cause disarrangement of the drop bars relatively to the contact rods. It has been found, however, that rigidly and fixedly holding the lease rods is 110

apt to put increasing frictional resistance upon the warp threads particularly if the attendant is careless in adjusting the warp or the harness.

In the type of stop motion herein disclosed, the leading members 10 and 11 serve not only the usual function, common in looms, of separating the warp threads in such manner that the warp feeds easily, and the threads are properly separated and control thereof for repair and manipulation is rendered easier, but in addition the leading members, which are constructed for conjoint movement with respect to each other or in any other suitable manner, serve the additional function of supporting the warp against the weight of the drop bars. Moreover, when the special form of drop bar here shown is used, the advantages incident thereto are obtained. By providing a construction and arrangement whereby the guiding means for the drop bars and the devices intended to coöperate with the drop bars in their indicating movement to stop the loom, are held in fixed relation so as not to partake of the movements of the leading members, and preferably are rigidly connected to the loom frame, while the warp supporting lease rods (not only separating the warp but supporting the same against the weight of the drop bars as above noted) are given a certain freedom of movement of any suitable character, with the movement preferably so confined as not to materially move the drop bars lengthwise of the warp, not only is more freedom given to the warp in its travel by the lease rods and through the drop bars, but greater certainty of stopping action of the stopping mechanism is obtained. A warp thread having broken, the drop bar falls and is guided by a stationary guide bar into contact or engagement with the lower co-acting device entirely free from any further movement that may be imparted to the warp supporting lease rods. Not only so, but the slight rocking or oscillatory movement of the lease rod or rods and the supported threads and drop bars tends, if anything, to increase the tendency of the released drop bar on the broken thread to fall. All the advantages, therefore, of permanently positioned guiding and stopping devices are had, together with the advantage of relatively freely moving warp supporting bars and lease rods.

To avoid the enumerated objections and other disadvantages I preferably construct each lease rod bracket 9 in two main parts although such other form of support may be employed as is found desirable. As indicated in Figs. 2, 3 and 4, these parts comprise a portion 18 herein shown as clamped to an angle bracket 2 and acting as a support for an arm or member 19, preferably pivoted thereto, as by bolts 19', to rock or oscillate in a vertical plane. Other means permitting vertical movement of the portion supporting the lease rods may be employed within the scope of my invention.

If desired, coil or other springs 20, 21, may be interposed between the oscillatory member 19 and the portion 18, as indicated in Fig. 3, to cushion the oscillatory movement of said member 19. The latter is adapted to support studs 22 which enter and sustain the lease rods 60 or members 10 and 11. While the said studs 22 may be if desired rigidly secured to or form a portion of the oscillatory member 19, I preferably mount them in any suitable manner permitting movement thereof toward and from the fell of the cloth, in order that as the beat 65 up of the lay occurs the lease rods may be movable to-

ward the fell of the cloth. This effect may be obtained in the manner indicated in Figs. 2, 3 and 4, wherein blocks 23 are mounted upon the oscillatory or vertically movable member 19 and have formed therewith the studs 22 extending through an open or slotted portion 24 of said member to permit the longitudinal movement of said studs and lease rods mounted thereon. I have shown cushioning members 25, herein represented as coil springs, interposed in the path of movement of said lease rods toward the fell of the cloth, thereby to afford a yielding support for said blocks, but I have found it to be sufficient to provide a cushioning member for merely the forward lease rod. It will be observed that in the form of the invention disclosed in Figs. 2, 3 and 4, the lease rods are mounted for movement independently of each other in addition to their common swinging movement. Warp supporting lease rods when mounted for independent movement when combined with guiding means for indicating drop bars and means coöperating with the loom stopping means 85 possess the advantages more fully hereinafter set forth.

In Figs. 5, 6 and 7 is shown a modified arrangement wherein upon the bracket 18 is mounted an oscillatory member 26, which receives a bridge portion 27 seated upon the upper face of the oscillatory member and having depending portions 28, 28, extending into longitudinally disposed slots in said member and having formed therein studs 22, 22, extending forwardly through openings 29, 29, in said member to receive the lease rods 10 and 11. If desired, a cushioning member, such for example as coil spring 30, may be interposed in the path of movement of the bridge portion toward the fell of the cloth. In this modified arrangement, it will be observed that the studs 22, 22 are rigidly united to move in unison. In Figs. 8 and 9 is shown still another modified arrangement wherein upon the bracket 18 is pivoted by bolt 31 an oscillatory member 32 having studs 22 extending forwardly therefrom. The bolt 31 is carried by a laterally sliding block 33 attached to or formed upon one face of the oscillatory member 32, said block 105 being mounted for such movement in elongated ways 34 in the oscillatory member. If desired, a coil spring or other cushioning member 35 may be interposed between one edge of the block and an adjacent portion of the oscillatory member to cushion the movement of the block and hence of the oscillatory member toward the fell of the cloth. While in these forms of the invention the portion or member mounted upon the bracket 18 is indicated as pivoted thereon, I am not to be restricted save as expressly stated to such manner of attachment. 115

In Fig. 1 is indicated an oscillatory member 36 mounted upon the bracket 18. In this form of the invention the lease rods carried by the member 36 are not shown as having a movement toward and from the fell of the cloth as in those other forms of the invention that are herein illustrated. Provision for such movement may or may not be made in such type of the invention. While I have shown several modified forms of my invention I desire it to be distinctly understood that my invention may be embodied in many other constructions 120 and arrangements and that I am in no wise to be limited to merely those forms that I have shown.

The provision of a yieldable oscillatory support, the pivotal point whereof is preferably located in or about the designed line of thread crossings, as represented in 130

Fig. 11, permits the lease rods to tip above or below the normal position shown in Fig. 11, and therefore permits the rods to align with the natural travel of the warp, without, however, supplying any material tendency 5 toward the displacement of the drop bars. The latter are sustained so close to the center of oscillation that a quite extensive tipping movement of the lease rods causes little or no movement of the drop bars.

In the practice of my invention, I have found that 10 the disclosed support for the lease rods is of marked advantage in reducing the friction upon the warp as evidenced by the great reduction in the amount of lint shed. By yieldingly supporting the lease rods the vibratory effect of the lay upon the warp is less apt to effect the 15 warp threads and the drop bars.

As shown in the drawings each bracket portion 9 may be provided with the upright head 36, to which may be fastened the guard strip or band of elastic or other material, represented by dotted line at 37. This guard strip, 20 as set forth in prior patent No. 747,856 to Coldwell & Gildard, may be used in substituting for the retaining rods 16 and 17.

While I have shown and described one form of my invention and as applied to a particular form of stop motion, it is to be understood that the same is not limited either in the detail of construction as disclosed or 25 form or relative arrangement of parts or to the specific application which is here made of the same, but that extensive modifications may be made in the illustrated 30 embodiment thereof without departing from the spirit of the invention.

Claims.

1. In a warp stop motion for a loom the combination with drop bars and guiding means therefor and cooperating circuit establishing means of warp supporting lease rods between which said drop bars are supported upon the leased threads of the warp and an oscillating support for said lease rods upon which said lease rods may move independently of the guiding means for said drop bars and circuit establishing means.
2. In a warp stop motion for a loom the combination with drop bars and cooperating circuit establishing means of warp supporting lease rods between which the drop bars are supported upon the leased threads of the warp, and a support for said lease rods having a tipping movement about an axis substantially coincident with the line of the thread crossings.
3. In a warp stop motion for a loom the combination with drop bars and guiding means therefor and cooperating circuit establishing means of warp supporting leasing members between which the drop bars are supported upon the leased threads of the warp, said leasing members being supported to permit movement thereof, whereby they may align with the natural travel of the warp, said support of the guiding means for the leasing members permitting such movement without movement of the drop bars.
4. In a warp stop motion for a loom the combination with drop bars and guiding means therefor and cooperating circuit establishing means of warp supporting leasing members and means wherein the same are mounted to move in conformity with the requirements of the warp such means permitting said movement of the leasing members without displacement of the guiding means for the drop bars.
5. In a warp stop motion for a loom the combination with circuit rods, drop bars in contact therewith, an underlying contact bar; warp supporting lease rods between which the drop bars are sustained out of contact with the contact bar by the leased threads of the warp, and a bracket sustaining said lease rods mounted for tipping movement about an axis substantially coincident with the line of crossed threads.

6. In a warp stop motion for a loom, the combination with one or more warp thread supporting lease rods, of one or more series of drop bars supported on the sheets of threads formed by said lease rod or rods, means for supporting said lease rod or rods upon the machine to permit movement thereof in conformity with the leveling requirements of the warp, fixed guiding means to guide the movement of an indicating drop bar, and fixed means to cooperate with said indicating drop bar to stop the loom. 75

7. In a warp stop motion for a loom, the combination with one or more lease rods dividing the warp into sheets of one or more series of drop bars supported on the sheets of threads formed by said lease rod or rods, said rod or rods being mounted upon the machine to permit movement thereof in conformity with the leveling requirements of the warp, guiding means to guide the movement of an indicating bar, and means to cooperate with said indicating drop bar to stop the loom, said guiding means and said cooperating means being supported to permit movement of the lease rod or rods independently of said guiding means and said cooperating means. 85

8. In a warp stop motion for a loom, the combination with a plurality of lease rods dividing the warp into sheets, a plurality of series of drop bars supported by the warp threads where so separated in sheets, guiding means to guide the loom stopping movement of the drop bars, and means cooperating with the loom stopping mechanism and with which an indicating drop bar is adapted to cooperate, 95 said guiding means and said means cooperating with the loom stopping mechanism being supported to permit movement of the lease rods independently thereof. 100

9. In a warp stop motion for a loom, the combination with a plurality of movable lease rods dividing the warp into sheets, a plurality of series of drop bars supported by the warp threads where so separated in sheets, guiding means to guide the loom stopping movement of the drop bars, and means cooperating with the loom stopping mechanism and with which an indicating drop bar is adapted to 105 cooperate, said guiding means and said means cooperating with the loom stopping mechanism being supported upon the loom frame. 110

10. In a warp stop motion for a loom, the combination with a plurality of movable warp thread supporting lease rods dividing the warp into sheets, a plurality of series of drop bars supported by the warp threads where so separated into sheets, guiding means to guide the loom stopping movement of the drop bars, and means cooperating with the loom stopping mechanism and with which an indicating drop bar is adapted to cooperate, said guiding means and said means cooperating with the loom stop mechanism being supported to permit compensating movement of the lease rods independently thereof. 115

11. In a warp stop motion for a loom, the combination with a plurality of movable warp thread supporting lease rods dividing the warp into sheets, one or more series of drop bars supported upon said sheets of warp between the lease rods, guiding means to guide the loom stopping movement of the drop bars, and means cooperating with the loom stopping mechanism and with which an indicating drop bar is adapted to cooperate, said guiding means and said means cooperating with the loom stop mechanism being supported to permit adjusting movement of the lease rods independently thereof. 120 125

12. In a warp stop motion for a loom, the combination with a plurality of movable warp thread supporting lease rods dividing the warp into sheets, a plurality of series of drop bars, the series being respectively supported upon the respective sheets of the warp between said lease rods, guiding means to guide the loom stopping movement of the drop bars, and means cooperating with the loom stopping mechanism and with which an indicating drop bar is adapted to cooperate, said lease rods being independently supported, so as to permit their warp caused movement 140 independently of any movement of said guiding means and means cooperating with the loom stopping mechanism. 145

13. In a warp stop motion for a loom, the combination with a plurality of lease rods dividing the warp into sheets, said lease rods being mounted to permit compensating 150 swinging movement thereof in conformity with the leveling movements of the warp, a plurality of series of drop

- bars supported by the warp threads where so separated into sheets, guiding means to guide the loom stopping movement of the drop bars, and means coöperating with the loom stopping mechanism and with which an indicating drop bar is adapted to coöperate, said lease rods being independently supported to permit their warp caused swinging movement independently of the said guiding means and means coöperating with the loom stopping mechanism.
- 10 14. In a warp stop motion for a loom, the combination of a plurality of leasing members dividing the warp into sheets and mounted for movement in conformity both with the leveling requirements of the warp and toward the fell of the cloth, one or more series of drop bars supported by the warp threads where so separated into sheets, guiding means to guide the loom stopping movement of the drop bars, and means coöperating with the loom stopping mechanism and with which an indicating drop bar is adapted to coöperate, said leasing rods being supported so as to permit their warp caused movement independently of any movement of the said guiding devices and said means coöperating with the loom stopping mechanism.
- 15 15. In a warp stop motion for a loom, the combination with a plurality of warp thread supporting lease rods mounted for independent warp caused movement, of one or more series of drop bars supported on the sheets of the threads formed by said lease rod or rods, guiding means to guide the movement of an indicating drop bar, and means to coöperate with said indicating drop bar to stop the loom, said guiding means and said coöperating means being supported independently of said lease rods.
- 20 16. In a warp stop motion for a loom, the combination with a plurality of lease rods mounted for independent warp caused movement and dividing the warp into sheets, a plurality of series of drop bars respectively supported upon the respective related series of sheets, and between said lease rods, guiding means to guide the movement of an indicating bar, and means to coöperate with said indicating drop bar to stop the loom, said guiding means and said coöperating means being supported to permit the described movements of said lease rods independently of said guiding means and said coöperating means.
- 25 17. In a warp stop motion for a loom, the combination with one or more lease rods dividing the warp into sheets of one or more series of drop bars supported on the sheets of threads formed by said lease rod or rods, said rod or rods being mounted upon the machine to permit movement thereof in conformity with the leveling requirements of the warp, cushioning means for such movement, guiding means to guide the movement of an indicating bar, and means to coöperate with said indicating drop bar to stop the loom, said guiding means and said coöperating means being supported to permit movement of the lease rod or rods independently of said guiding means and said coöperating means.
- 30 In testimony whereof, I have signed my name to this specification, in the presence of two subscribing witnesses.

JAMES K. LANNING.
